UNITED STATES PATENT OFFICE.

MORIZ BAUER, OF VIENNA, AUSTRIA-HUNGARY.

DESIGN FOR AN INHALER.

SPECIFICATION forming part of Design No. 34,994, dated August 27, 1901.

Application filed September 6, 1900. Serial No. 29,235. Term of patent 7 years.

To all whom it may concern:

Be it known that I, MORIZ BAUER, physician, a citizen of the Empire of Austria-Hungary, residing at Vienna, in the Province of Lower Austria, in the Empire of Austria-Hungary, have invented a new and original Design for an Inhaler; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The drawings illustrate an inhaler embodying my design, Figure 1 being a view thereof in side elevation, Fig. 2 a view in transverse section on either of the planes indicated by the broken lines 2 2 of Fig. 1, and Fig. 3 a

view in transverse section on the plane indicated by the broken line 3 3 of Fig. 1.

In the drawings, *a* indicates the body of the inhaler, having the form of an egg and terminating at its ends in two straight cylindrical tubes *b* and *c* of equal diameter, projecting from the ends thereof, as shown.

Having thus fully described my invention, what I claim as new, and desire to secure by Letters Patent of the United States, is—

The design for an inhaler, substantially as herein shown and described.

In testimony that I claim the foregoing as my invention I have signed my name in presence of two subscribing witnesses.

MORIZ BAUER.

Witnesses:

FRIEDRICH BINDLE,
ALVESTO S. HOGUE.
